VAPORIZER FOR MOISTURIZING THE SKIN

Nancy M. D'Alesandro, 245 Albermarle St.,
Baltimore 2, Md.

Filed Jan. 30, 1962, Ser. No. 68,601

Term of patent 14 years

(Cl. D83—1)

FIG. 1

FIG. 2

FIG. 3

FIG. 4

FIG. 1 is a perspective view of a vaporizer for moisturizing the skin incorporating my new design;

FIG. 2 is a front elevation thereof;

FIG. 3 is a side view taken 90° to the front view of FIG. 2; and

FIG. 4 is a top view thereof.

I claim:

The ornamental design of a vaporizer for moisturizing the skin, as shown and described.
